APPARATUS FOR DETERMINATION OF THE TEMPERATURE OF DEPOSITION OF ELECTRICALLY NONCONDUCTING SOLIDS FROM GASES

Thomas John Webster, London, England, assignor to The British Oxygen Company Limited, London, England

Application April 2, 1952, Serial No. 280,116

Claims priority, application Great Britain April 9, 1951

3 Claims. (Cl. 73—17)

1

This invention relates to a method and apparatus for the determination of the temperature of deposition of an electrically non-conducting solid from a gas, such as, for example, the determination of the so-called "ice point" of a gas, that is the temperature at which ice is deposited from a gas containing water vapour at so low a concentration that the gas becomes saturated with water vapour at a temperature below 0° C. so that the water vapour is deposited in the form of ice when the temperature of the gas falls below its saturation point. A knowledge of the ice point allows the humidity of the gas readily to be calculated. For the sake of clarity, the invention will throughout be described with reference to the determination of the temperature of deposition of ice from a gas, but it will be appreciated that it may similarly be employed for the determination of the temperature of deposition of any other electrically non-conducting solid from a gas.

Hitherto, the determination of the ice point of a gas has depended upon visual or photoelectric observation of the formation of an ice film on a suitable surface which is progressively cooled in contact with the gas. Such visual observation cannot be made with a gas at high pressure, owing to difficulties in construction imposed by the necessity for using transparent materials, and in such cases it is accordingly necessary to expand the gas to a relatively low pressure before making the determination, thereby decreasing the sensitivity of the method.

A further source of error in the determination lies in the fact that certain gases, for example, air, tend to become supersaturated with water on being cooled below the condensation point, so that the observed ice-formation takes place at a temperature below the true ice point.

It is an object of the present invention to provide an apparatus for the determination of the temperature of deposition of ice or other electrically non-conducting solid from a gas which can be used directly for gases either at high or low pressure and which for a considerable range of temperatures of deposition are not subject to errors caused by supersaturation of the gas at the condensation temperature.

It is a further object of the invention to provide an apparatus which can be made fully automatic in its operation and can be adapted to operate continuously.

According to a further feature of the invention, apparatus for the determination of the temperature of deposition of ice or other electrically

2

non-conducting solid from a gas comprises an electrical conductor arranged to form part of an electrical circuit, means for making and breaking the circuit at frequent intervals at the surface of the conductor, means for passing a stream of gas over the said surface, means for progressively reducing the temperature of the said conductor and means for recording the temperature of the surface of the conductor exposed to the gas stream at which completion of the electrical circuit ceased to take place owing to the formation of a deposit of the electrically non-conducting solid on the surface.

The electrical conductor is preferably of metal adapted to be cooled at a controlled rate and is made to form part of an electric circuit which is closed at frequent intervals by causing the free end of an electrically conducting feeler, for example a metal wire, also included in the circuit to touch the surface of the conductor exposed to the gas stream. This surface is preferably polished or plated to ensure good electrical contact. The motion of the feeler towards or away from the surface may be effected by hand or preferably mechanically, for example by a motor-driven cam mechanism.

The completion of the circuit may if desired be indicated each time the feeler touches the surface by a micro-ammeter or other sensitive electrical device incorporated in the circuit, the temperature of the surface being continuously measured by means of a thermocouple or other temperature measuring device in intimate contact therewith. In operation, a slow stream of gas whose ice point is to be determined is passed over the surface of the conductor and the temperature of the latter progressively reduced. As soon as the ice point of the gas is reached, ice begins to condense on the cooled metal surface and formed thereon an insulating layer which interferes with the completion of the electrical circuit when the feeler is subsequently brought into contact with the surface. The failure of the wire to complete the circuit as indicated by the lack of reaction by the micro-ammeter indicates that the ice point has been reached and the temperature of the surface at the instant when this failure first occurs is recorded as the ice point temperature.

Alternatively, the system can readily be made fully automatic in operation; for example, the failure of the feeler to complete the circuit may be made to operate an automatic temperature-recording device by a suitable system of relays. Further, after recording the temperature, the

3

relay system may be made to operate a heating device to raise the temperature of the surface sufficiently to remove the ice deposited thereon, and thereafter to restore the system to its original condition. By this means, the apparatus can be adapted automatically to provide a continuous series of readings of the ice point of the gas stream.

A convenient method of cooling the metal surface at a controlled rate is to form the surface at one end of a tube or rod of copper or other metal of high heat conductivity and to immerse the other end of the rod or tube in a bath of refrigerant, such as, for example, liquid oxygen or liquid nitrogen. The rate of cooling may be controlled by adjusting the depth of immersion of the rod or tube in the refrigerant bath, or by heating an intermediate portion of the rod or tube in a controlled manner. Alternatively, the tube or rod may consist of two sections of copper joined by a section, for example of brass, acting as a thermal resistance, in which case the rate of cooling will be independent of the depth of immersion of the rod or tube in the refrigerant, so long as only the lower section of copper is so immersed.

In using the apparatus of the present invention to determine the ice point of a gas, it has been found that when the ice point is below about -20°C . the ice film is not deposited uniformly over the whole of the surface of the conductor exposed to the gas stream but forms preferentially at the point of contact between the surface and the contacting feeler. This effect increases considerably the sensitivity of the method since it localises the formation of the effective ice film within a very small area. Moreover, the moving contact tends to "seed" the formation of ice crystals from the gas which prevents the gas from becoming supersaturated with water vapour as it is cooled below the condensation point.

Since the present method does not depend upon visual or photoelectric observation for detection of the ice film, when the ice point of a gas at high pressure is to be determined, the detecting device may be totally enclosed within an opaque vessel constructed of material capable of withstanding the pressure of the gas. It is therefore unnecessary to expand the gas to a low pressure before the determination and the sensitivity of the method is thereby maintained.

At atmospheric pressure it has been found that the ice point of air saturated at a temperature as low as -100°C . can be determined by the method of the present invention within an accuracy of one or two degrees centigrade.

The invention will now be more particularly described with reference to the accompanying drawings which illustrate one form of apparatus according to the invention adapted automatically to provide a continuous series of determinations of the ice point of a gas at atmospheric pressure.

In the drawings

Figure 1 shows in diagrammatic side elevation the apparatus proper; and

Figure 2 shows diagrammatically the relay system associated therewith.

Referring to Figure 1, a feeler 1 consisting of a short length of fine platinum wire, is attached to one end of a thin strip 2 of spring material, the other end of which is adjustably fixed to one end of a cam-follower 3, the relative positions of strip 2 and cam-follower 3 being adjustable.

4

by means of a screw 4. The cam-follower 3 is formed with a right-angled bend and is mounted to pivot at the bend on a fixed horizontal pivot 5. The feeler 1 is caused to perform a vertical reciprocating motion by a cam 6 rotating about a spindle 7 driven by a synchronous motor (not shown) at a suitable speed, against the surface of which cam a projection 8 from the end of the cam-follower 3 to which the feeler 1 is attached bears.

At the bottom of its stroke the feeler 1 makes contact with the end 9 of a copper rod 10, this contact being made at suitable intervals and maintained for about 0.5 second. Both the feeler 1 and the rod 10 are included in an electrical circuit forming part of the relay system as hereinafter described. The force between the feeler 1 and the end 9 of the rod 10 may be adjusted by means of a screw 11 which acts as a stop for the end of the cam-follower 3 remote from the feeler 1 and thus controls the position of the lower end of the stroke. The time for which contact is made may be adjusted by means of the screw 4 controlling the position of the feeler 1 relative to the cam-follower 3.

A second cam-follower 12, also pivoted at a right angled bend on the horizontal pivot 5, is provided at the end adjacent to the cam 6 with a threaded extension 13 on which works on a nut 14 which bears against the surface of the cam. The other end of the cam-follower 12 carries an electrical contact 15 which is caused by the movement of the cam-follower 12 to touch momentarily a screw 16, during the period when the feeler 1 is touching the surface 9 of the rod 10; that is it makes contact after the feeler 1 touches the surface 9 and breaks contact before the feeler leaves the surface. The time of operation of this contact relative to that of the feeler 1 may be varied by altering the position of the nut 14 on the threaded extension 13. Both the contact 15 and the screw 16 are included in an electrical circuit forming part of the relay system as hereinafter described. The cam-followers 3, 12 are constrained to follow the cam surface by springs 17, 18 attached to their respective lower ends.

The surface 9 of the copper rod 10 is plated with rhodium or other electrically conducting protective material to prevent corrosion and to give a good electrical contact, and acts as the cool surface on which deposition of ice occurs. A thermocouple 19 passes axially up the rod 10 its operating junction being located close behind the surface 9. The thermocouple 19 is connected to a dotting recorder of conventional pattern (not shown) which records the temperature of the surface 9 on a continuous motor-driven chart by means of a chopper bar mechanism actuated by the relay system as hereinafter described. A heater 20 is wound round the rod 10 near the top thereof for removal of frost.

The lower end of the rod 10 has screwed to it a brass rod 21 to which is in turn screwed a further length of copper rod 22 which is immersed in a liquid oxygen bath (not shown). The brass rod 21 acts as a thermal resistance so that the rate of cooling of the surface 9 is independent of the level of liquid oxygen so long as the lower section 22 of copper and this alone is immersed.

The surface 9 of the rod 10 is enclosed in a housing 23 of a transparent material which is provided with a gas entry port 24 and a gas exit 25, the latter in this example also serving as an entry for the feeler 1. The housing 23 has the

double function of directing the stream of gas to be tested against the surface 9 and of excluding atmospheric air.

In operation, a stream of the gas to be tested is passed through the housing 23 and the surface 9 is progressively cooled while the feeler 1 continues to contact the surface 9 at regular intervals, thus making and breaking regularly the electric circuit. As soon as frost appears on the surface 9 when the ice point is reached, the feeler can no longer complete the circuit and a relay system is operated as hereinafter described to effect the sequence of operations involving (1) recording the temperature, (2) thawing off the frost and (3) re-cooling the rod 10.

This sequence is performed automatically and repeatedly by means of the circuit shown in Figure 2. The relays are shown therein in the position corresponding to that part of the sequence during which the rod 10 is being cooled and before frost has been produced. Relay R3 is the operating relay of a conventional post office rotary selector having six rotating contacts C1-C6, shown in the figure as each having four positions. These contacts are connected as follows:

C1 at the fourth position closes a circuit including the relay R3 and a switch S3 normally closed;

C2 at the second position closes a circuit including the chopper bar motor of the temperature recording device connected directly to a main source of alternating current at 230 v.;

C3 at the second position closes a circuit including the relay R3 and a switch S5 actuated by the chopper bar of the instrument recording the temperature of rod 10 as hereinafter described;

C4 at the third position closes a circuit including the relay R3 and also including switch S6 through a conventional amplifier indicated at A within the panel enclosed by the broken line, the switch S6 being operated by the pointer of the instrument recording the temperature of rod 10 as hereinafter described;

C5 at the first position closes a circuit including switch S4, relay R2 and the contacts 15 and 16; and

C6 at the second and third positions closes a circuit including the heater 20 and a warning lamp L in parallel therewith.

Each of these circuits includes the requisite source of alternating or direct current at the appropriate voltage, such current being obtained from the main voltage source through the necessary transformers and rectifiers.

In operation, when the rod 10 is being cooled, the contacts C1-C6 will be in the position shown in the diagram. When the feeler 1 makes contact with the surface 9 of the rod 10, it completes a circuit including the moving-coil relay MMCR which opens switch S4 in series with the contact 15, so that when contacts 15 and 16 touch during the period when the feeler 1 and surface 9 are in contact as hereinbefore described, no current flows through the circuit including contact C5. When frost first appears on the surface 9, however, the feeler 1 does not make electrical contact with the surface 9 so that switch S4 remains closed; hence when the contact 15 touches the screw 16 the circuit including contact C5 is completed energising relay R2.

Relay R2 closes switch S2 thus in turn energising relay R3 which moves the contacts C1-C6 to the second position, and at the same time opens switch S3 which de-energises relay R3. Contacts

C6 and C2 switch on the heater 20 and the chopper bar motor respectively. When one dot recording the temperature of the surface 9 has been recorded, the movement of the chopper bar closes the switch S5 which is coupled thereto and completes the circuit through contact C3 again energising relay R3 and moving the contacts C1-C6 into the third position.

During this period the heater remains on until the temperature of the rod 10 has been raised to a predetermined value at which all the frost has been evaporated from surface 9, when the switch S6 attached to the pointer of the temperature recording instrument closes and operates the relay R3 through the amplifier A. The contacts C1-C6 are moved to the fourth position when contact C1 completes a circuit again energising relay R3 and thus restoring the contacts C1-C6 to the first position and the system to its initial condition.

By the use of this instrument a series of readings of the ice point of the gas stream can be taken automatically over as long a period as may be desired.

25 I claim:

1. Apparatus for the determination of the temperature of deposition of an electrically non-conducting solid from a gas which comprises an electrical conductor arranged to form part of an electric circuit, an electrically conducting feeler also included in said electric circuit, means for making and breaking contact between the surface of said conductor and an end of said feeler at frequent intervals thereby making and breaking the circuit at frequent intervals at the surface of the conductor, means for passing a stream of the gas over the said surface, means for progressively reducing the temperature of said surface and means for indicating the temperature of said surface at which completion of the electrical circuit ceases to take place owing to the formation of a deposit of the electrically non-conducting solid on said surface.

2. Apparatus for the determination of the temperature of deposition of an electrically non-conducting solid from a gas which comprises an electrical conductor arranged to form part of an electric circuit, an electrically conducting feeler also included in said electric circuit, means for making and breaking contact between the surface of said conductor and an end of said feeler at frequent intervals thereby making and breaking the circuit at frequent intervals at the surface of the conductor, means for passing a stream of the gas over the said surface, means for progressively reducing the temperature of the said surface, temperature recording means, and relay means operable automatically on the failure of the circuit to be completed owing to the formation of a deposit of the electrically non-conducting solid on said surface to actuate said temperature recording means to record the temperature at which such failure occurs.

3. Apparatus for the determination of the temperature of deposition of an electrically non-conducting solid from a gas which comprises an electrical conductor arranged to form part of an electric circuit, an electrically conducting feeler also included in said electric circuit, means for making and breaking contact between the surface of said conductor and an end of said feeler at frequent intervals thereby making and breaking the circuit at frequent intervals at the surface of the conductor, means for passing a stream of the gas over the said surface, means

for progressively reducing the temperature of the said surface, temperature recording means, heating means for raising the temperature of said conductor, and relay means operable automatically on the failure of the circuit to be completed owing to the formation of a deposit of the electrically non-conducting solid on said surface first to actuate said temperature recording means to record the temperature at which such failure occurs and thereafter to actuate said heating means until the temperature of said surface has been raised to a predetermined value sufficiently high to ensure that all the electrically non-conducting solid deposited on said sur-
